UNITED STATES PATENT OFFICE.

CARL JAMES LANG, OF OLEAN, NEW YORK.

CARBON-HOLDER FOR ELECTRIC LAMPS.

No. 811,411.

Specification of Letters Patent.

Patented Feb. 2, 1909.

Application filed April 30, 1908. Serial No. 430,184.

To all whom it may concern:

Be it known that I, CARL J. LANG, a citizen of the United States, residing at Olean, in the county of Cattaraugus and State of New York, have invented certain new and useful Improvements in Carbon-Holders for Electric Lamps, of which the following is a specification, reference being had to the accompanying drawings.

10 My invention relates to improvements in carbon holders for electric arc-lights or lamps, and it consists of the novel features of construction and the combination and arrangement of parts hereinafter fully described and claimed.

15 The object of the invention is to provide a simple and practical device of this character by means of which the carbon pencil may be securely clamped in an adjusted position and 20 which will be effectively insulated from the other portions of the lamp.

25 The above and other objects of the invention, as will hereinafter appear, are attained in its preferred embodiment illustrated in the accompanying drawings, in which—

30 Figure 1 is a plan view of my improved carbon holder; Fig. 2 is a side elevation of the same; Fig. 3 is a longitudinal section; and Fig. 4 is a detail transverse section taken on the plane indicated by the line 4—4 in Fig. 1.

35 My improved carbon holder comprises an adjustable arm 1 composed of two sections 2, 3 which are insulated from each other but rigidly connected, one section carrying a clamping device for the carbon pencil or stick and a binding post or connection for one terminal of the electric circuit and the other section being adjustably connected to 40 the supporting or attaching member 4 which is arranged upon the feed mechanism of the lamp. The insulating joint between the sections 2, 3 of the arm 1 is formed by squaring the inner ends of said sections and recessing 45 their opposing faces, as at 5, so that they fit each other and forming said overlapping or interlocking ends with aligned openings 6 to receive a clamping bolt or the like 7. A bushing or sleeve 8 of mica or other insulating material is arranged upon the bolt in the opening 6 and the head of said bolt is preferably countersunk or flush with the outer face of the section 2, as shown, the other threaded end of said bolt having a clamping 50 nut arranged upon it. A strip of mica or the like 9 is also arranged between the recessed

and overlapping inner ends 5 of the sections 1, 2 to effectively insulate one from the other. The section 3 of the arm has its outer end pivoted in a forked portion 10 of 60 the attaching member 4 and it is adapted to be clamped in an adjusted angular position in said portion 10 by its pivoting screw 11. The latter has at one end a shouldered enlargement and a head or finger piece 12 and 65 at its other end screw threads which engage a threaded opening in one branch of the forked portion 10. The forked portion 10 of the attaching member is offset from its body portion, which latter is formed with a vertical 70 opening 4^a to receive one of the feed bars of an arc-light feed mechanism of any form and construction. Said body portion of the member 4 is also formed with a horizontal socket 4^b which opens into the vertical opening 4^a, said socket being of such size as to receive the feed bar and thereby permit the holder to be disposed either vertically or horizontally.

75 When the feed bar is arranged in the vertical opening 4^a the attaching member or body 4 will be disposed horizontally and the adjustably pivoted arm 1 will also be disposed horizontally or approximately so; but when said feed bar is arranged in the socket 80 or opening 4^b the attaching member or body is turned on the pivot 11 to a vertical plane or at right angles to the arm 1, which latter is always disposed in a horizontal or approximately horizontal plane. The provision of 85 the socket 4^b also permits the attaching member or body 4 to be secured on any horizontal stud or projection that may be on the feed bar.

90 A set screw 13 is arranged in a threaded opening in the body portion of the attaching member at a point opposite the intersection of the openings or sockets 4^a, 4^b so that it will impinge against the feed bar when inserted in either of said openings or sockets. The section 2 of the vertical swinging arm 1 has its outer end enlarged and formed with a transverse groove or recess 14 which forms one jaw of a carbon clamp, the other similar jaw 15 of which is formed by a plate 16 hinged at one end to the outer end of the section 2 and adapted to have its other or free end secured to the inner portion of the section 2 by means of a screw 17 and a clamping nut 18. The screw 17 is pivoted at 19 in a recess or slot formed in the section 2 and it is 100 adapted to swing into and out of a notch or

slot 20 formed in the free end of the jaw member 16. The nut 18 is preferably provided with wings and with a stationary washer or flange which bears against the outer face of the jaw member 16. The hinge connection between the two jaw members is preferably formed by bifurcating the outer end of the section 2 and reducing the inner end of the jaw member 16, as shown at 21, 10 and securing said reduced end 21 in the bifurcated portion of the section 2 by means of a pivot pin 22.

23 denotes a post projecting from the member 2 and formed with a socket to receive one of the terminals of the electric circuit. The wire may be secured in the socket by a set screw 24.

By providing the adjustable pivotal connection comprising the parts 10, 11 between 26 the attaching member or body 4 and the carbon supporting arm 1 and by making said arm of rigidly and permanently connected insulated sections and attaching the circuit wire to the outer section which carries the 25 carbon, it will be seen that the inner section of said arm may be swung or tilted to any angle and securely clamped in such position without danger of wearing or weakening the insulated joint or connection between the 30 two sections of the arm. This construction renders the invention exceedingly effective for use on arc lamps used in moving picture machines because it is frequently necessary to adjust the carbon both vertically and angularly in order to secure an effective light.

Having thus described my invention what I claim is:

1. A device of the character described comprising an attaching member having a 40 body portion formed with intersecting sockets or openings to receive the feed rod of an arc-lamp, a set screw arranged in a threaded opening in the body portion and adapted to impinge against the feed rod inserted in 45 either of said openings or sockets, an adjustable arm carried by the body portion and consisting of rigidly connected sections insulated from each other and means upon said arm for supporting a carbon.

50 2. A device of the character described comprising an attaching member having a body portion formed with intersecting sockets or openings to receive the feed rod of an

arc lamp, a set screw arranged in the threaded opening in the body portion and adapted 55 to impinge against the feed rod inserted in either of said openings or sockets, said body portion being also formed with a forked portion having alining apertures in its branches, the aperture in one branch being screw 60 threaded, a carbon carrying arm consisting of insulated sections and having an apertured end arranged between the branches of the forked part of the body portion and having its aperture in alinement with the apertures in said branches, a thumb screw arranged in said alining apertures and having a shoulder at one end to engage one of said branches and a threaded portion at its other end to engage the threads in the aperture of 70 the other branch whereby said arm is pivotally mounted and may be clamped in any angular position with respect to the body portion of the attaching member, means upon the outer section of the arm for securing a carbon thereto and means upon said outer section of the arm for the attachment of a circuit wire.

3. A device of the character described comprising an attaching member having a 80 socket or opening to receive the feed rod of an electric lamp, a set screw for rigidly securing said member to the feed rod, said member being also formed with a forked portion having spaced branches provided with alining 85 apertures, one of the latter being screw threaded, a carbon carrying arm consisting of insulated sections and having one end apertured to enter between the spaced branches of the forked portion of the member 90 and to have its aperture aline with those in said branches, and a clamping screw arranged in said alining apertures and having a shoulder at one end to engage one of said branches and a threaded portion at its other 95 end to engage the threads in the aperture of the other branch whereby said arm is pivotally mounted upon the member and may be clamped in any angular position with respect thereto.

In testimony whereof I hereunto affix my signature in the presence of two witnesses.

CARL JAMES LANG.
